UNITED STATES PATENT OFFICE

157,270

ANIMATED DISPLAY DEVICE

Aubrey B. Leech, Los Angeles, Calif.

Application April 7, 1947, Serial No. 138,195

Term of patent 14 years

(Cl. D1—2)

To all whom it may concern:

Be it known that I, Aubrey B. Leech, a citizen of the United States of America, residing in the city of Los Angeles, in the county of Los Angeles, State of California, have invented a new, original, and ornamental Design for an Animated Display Device, of which the following is a specification, reference being had to the accompanying drawing, forming a part thereof.

Fig. 1 is a top plan view of the animated display device, showing my new design;

Fig. 2 is a front elevational view with the cover in opened position;

Fig. 3 is a side elevational view;

Fig. 4 is a front elevational view taken on the line 4—4 of Fig. 3; and

Fig. 5 is a front elevational view thereof with the cover closed.

The picture in Fig. 2 is of contrasting appearance and Figs. 3 and 4 are shaded for contrasting appearance.

I claim:

The ornamental design for an animated display device, as shown and described.

AUBREY B. LEECH.
